UNITED STATES PATENT OFFICE

FREDERICK C. OVERBURY, OF HILLSDALE, NEW JERSEY, ASSIGNOR, BY MESNE ASSIGNMENTS, TO THE PATENT AND LICENSING CORPORATION, OF BOSTON, MASSACHUSETTS, A CORPORATION OF MASSACHUSETTS

ROOFING ELEMENT

Application filed May 15, 1928. Serial No. 277,950.

This application relates to roofing elements such as shingles, shingle strips, and the like, which are characterized by an upturned portion of the element along its butt edge, this upturned portion being for the purpose of facilitating the application of plastic material to the exposed face of the shingle when laid. This application is furthermore a continuation-in-part of my co-pending application Serial No. 651,097, filed July 12, 1923. Such plastic may be conveniently applied as by a trowel or other suitable instrument, the object being to form on the laid roofing element a thick layer or coating of plastic which can readily be shaped so as to give the appearance of rough tiling, heavy slabs, tapering elements, or other forms of finished roofing elements as desired. An object of the present invention is to supply an element of roofing material which is particularly adapted to assist in the application of plastic by a trowel and to guide the trowel. To this end, a relatively narrow marginal portion along the butt edge of the roofing element may be bent sharply upward so as to form an angle with the plane of the roofing element. The butt edge of the element is thus elevated a predetermined distance above the plane of the element; thus affording a ready guide for the trowel to determine the thickness of the coating of plastic applied to the exposed face of the element after it is laid on a roof. This upturned margin or ridge also serves to retain the plastic in place and to assist the plastic to hold its shape after application.

For a more complete understanding of the invention, reference is had to the description which follows and to the drawing, of which,—

Figure 1 is a perspective view of a roofing element embodying the invention.

Figure 2 is an end elevation of the element shown in Figure 1.

Referring to the drawing in detail, 10 represents a roofing element which may be in the form of a strip shingle as illustrated, or may be in the form of an individual shingle or a strip of roll roofing. Whatever the shape or size of the roofing element, it will

have a certain portion which will be exposed to the weather when laid with other similar elements on a roof. Along the butt edges of the element, a relatively narrow marginal portion 11 is bent upwardly through an angle which may be approximately 90° but, as shown in Figure 2, is preferably somewhat less. This bend results in a ridge extending along the entire butt edge of the roofing element and projecting outwardly and upwardly from the body portion of the element. It is apparent that if such an element is laid on a roof, suitable plastic material may be rapidly and easily troweled on to the exposed face of the element. In shaping the plastic after its application to the face of the element, the trowel or other tool may be run along on the edge of the upturned portion 11, so that this portion acts as a positive guide for the trowel. While it is often desirable to lay a roof the final appearance of which is one of pleasing irregularity, such a result is not the same thing as that from irregularities which arise from obviously poor workmanship. The presence of the guiding edge 12 tends to minimize the possibilities of unpleasing results due to careless or poor workmanship and to facilitate the formation of artistic and pleasing irregularities.

In the application of plastic to a roof, some of the plastic may also be applied under the upturned portion 11, that is, between this portion and the face of the element in the course next below on the roof. Thus the rib 11 may and preferably is entirely embedded or buried in plastic when the roof is finished, the plastic applied to the face of the element above the rib 11 being smoothed over the edge 12 of the rib to bond with plastic applied under the rib. The plastic may, if desired, be applied in variegated colors which may be manipulated to produce a large variety of effects.

The element 10 may be made of any suitable material which can be readily bent as described. Such material may comprise a base of felted fibers thoroughly saturated with asphalt. This saturated base may, if desired, have a coating of asphalt thereon al-

though this is not necessary if the plastic which is to be applied to the element when laid is thoroughly waterproof in character. If the plastic is asphaltic in composition, it will bind readily with the elements 10 made as described. The element 10 may also be made of finished asphaltic roofing which in addition to a coating of high melting-point asphalt is surfaced with a layer of crushed 10 grit or the equivalent partially embedded in the asphalt coating. Roofing material of this general description, with or without a coating of high melting-point asphalt or a surfacing layer of grit, is semi-flexible in character and may be readily bent through a moderate angle at ordinary temperatures such as 15 70° F., no especial heating being required to effect a successful bend. When thus bent, such material will ordinarily hold its bent 20 shape indefinitely.

Having thus described certain embodiments of this invention, it should be evident to those skilled in the art that various changes and modifications might be made therein 25 without departing from its spirit or scope as defined by the appended claims.

I claim:

1. An individual roofing element having the marginal portion along the butt edge 30 thereof bent upwardly and extending at an angle to the plane of the element.
2. An individual roofing element having the marginal portion along the butt edge thereof bent upwardly so that it extends away 35 from the body of the element and makes an acute angle with the plane thereof.
3. A strip shingle having a relatively narrow marginal portion along the butt edge thereof bent upwardly from the plane of the 40 shingle through an acute angle.
4. A roof comprising a plurality of elements of sheet material, each element having an upturned portion along its butt edge, and plastic material overlying said elements and 45 embedding said upturned portions.
5. A roof comprising a plurality of elements of sheet material, each element having an upturned portion along its butt edge, and plastic material of variegated colors overlying 50 said elements and embedding said upturned portions.
6. A roof comprising a plurality of elements of fibrous and asphaltic sheet material, each element having an upturned portion 55 along its butt edge, and asphaltic plastic material overlying said elements and embedding said upturned portions.

In testimony whereof I have affixed my signature.

69 FREDERICK C. OVERBURY.
